ASH TRAY

Leo Lowi, Asbury Park, N. J.

Application May 16, 1955, Serial No. 36,001

Term of patent 14 years

(Cl. D85—2)

Fig. 1 is a top plan view of an ash tray, showing my new design;

Fig. 2 is a bottom plan view thereof;

Fig. 3 is a front elevational view thereof; and

Fig. 4 is a cross-sectional view thereof, taken on the line 4—4 of Fig. 1.

The drawing figures are diagonally lined to indicate transparency.

I claim:

The ornamental design for an ash tray, as shown and described.
